[57] CLAIM

The ornamental design for a carrying case for a portable toilet, as shown and described.

DESCRIPTION

FIG. 1 is a perspective view of a carrying case for a portable toilet showing my new design;

FIG. 2 is another perspective view thereof showing the cover in an open position;

FIG. 3 is a front elevational view thereof;

FIG. 4 is a rear elevational view thereof;

FIG. 5 is a side elevational view thereof, the opposite side being a mirror image of the side shown;

FIG. 6 is a top plan view thereof; and,

FIG. 7 is a bottom view thereof.

The broken line representation of a portable toilet in FIG. 2 is for purposes of illustration only and forms no part of the claimed design.
